EXTERIOR OF THE FRONT OF A RESTAURANT BUILDING

Albert J. Miller, San Jose, Calif., assignor to Norfish
Sales Company, Inc., Oakland, Calif., a corporation of California

Filed June 9, 1969, Ser. No. 17,608

Term of patent 14 years

Int. Cl. D25—01

U.S. Cl. D13—1

Fig. 1

Fig. 2

FIG. 1 is a front perspective view of the exterior of the front of a restaurant building showing my new design; and

FIG. 2 is a side elevational view thereof.

I claim:

The ornamental design for an exterior of the front of a restaurant building, substantially as shown.
